ABSTRACT

A method for cleansing the exterior surface of a building of masonry, stone, brick or the like by which a jet of water at a temperature of not less than 100°C. is directed by a nozzle in close juxtaposition to such surface under a pressure of about 20 atm. so that the larger quantity of water does not vaporize before touching the surface to be cleaned. As a result, the water vaporizes either on or in the exterior coating of the surface being cleaned so that when expanding the steam presses the dirt etc. from the pores, capillaries and fissures of the surface. A solution is brushed or sprayed on the cleansed surface to render it water resistant.

1 Claim, No Drawings

METHOD FOR CLEANSING SURFACES OF BUILDINGS AND PASSAGE-WAYS

BACKGROUND OF THE INVENTION

The invention deals with a technique as to how to treat surfaces of buildings and passage-ways, as also bridges and airport tarmacs. The invention is based on the use of heated water, which is sprayed against the area which is to be cleansed.

In consequence of the increasing air pollution by, among a number of other things, automobiles and industry, the problem of pollution and destruction of buildings has become a lot more obvious. The destruction is connected with the entrance of such aggressive exhaust components as sulphur dioxide dissolved in water and turned to sulphuric acid which in pores and capillary tubes thus penetrate the exterior areas. The result is that the exterior areas decay. There are sufficient examples, especially on the European mainland, which clearly show and prove that irretrievable and valuable buildings, sculptures and diverse cultural monuments, have suffered extensive damage due to these attacks on them by environmentally damaging materials. Mostly endangered are, of course, soft materials, such as sandstone and limestone, which were the most frequently and extensively used for building materials in the past.

To preserve and maintain invaluable and irreplaceable treasures as cultural monuments, on the one hand, and combat destructive effects to modern buildings on the other hand, it has been appreciated after recognition of the necessity, that the surfaces of buildings and passage-ways be treated by washing and impregnation to make these insensitive with regard to the all destructive effects of polluted air.

There are various cleansing methods available. The most usual being the method utilizing water, steam or a chemically composed cleansing solution. Hot water is used, among other purposes, to cleanse automobiles, oil tanks, and many more severely dirtied surfaces of metal or similar material. One well known method involves the utilization of chemical preparations in connection with water under high pressure.

After this, the dirt which has just been loosened with the aid of this chemical solution is washed off by the high pressure water spray. For this operation, a pipe is used where the nozzles are positioned at approximately one meter or more above the dirty surface. The disadvantage of this cleansing method is that the chemicals which are applied to the area to be cleansed through the subsequent high pressure washing are forced into the pores of the material and stay there. Apart from this fact, high pressure washing as used damages the material.

After cleansing, the surface area is generally impregnated with a preparation, as for example, with silicic acid solution. However, as it has not as yet been possible in the case of known and practiced methods of cleansing to cleanse the pores and capillaries, the molecules of the impregnation medium are not firmly anchored deeply enough with the exterior coat of the material, thus these are readily loosened again as for example, when subjected to the power of rain downpours, hailstones, and the like.

SUMMARY OF THE INVENTION

This invention relates to a method of depth cleansing

of exterior surfaces of buildings and passage-ways of masonry, stone, brick, and the like and which is based on the use of hot water under relatively high pressure. The heated water is forced with great power into the pores of the exterior surface. There it is vaporized. In the process, salt residue, chemicals, dirt collection, water residue, etc. are catapulted out. The surface thus treated has applied to it an impregnation solution once or several times, as required. As a result, the exterior surface acquires a water resistant quality which permits a vapor diffusion out of the building wall into the atmosphere.

DESCRIPTION OF THE PREFERRED EMBODIMENT

The method in accordance with the invention is thus mainly determined in that the exterior surface is cleansed by water at a temperature of more than 100°C forced under pressure through a nozzle which is held at an almost exact right angle against the area to be cleansed. The nozzle is guided translatorily parallel to the surface to be cleansed. The nozzle should be no more than 2 cm from the area to be cleansed so that most of the water particles do not vaporize before the jet touches the surface, whereby the water either on or in the surface coat finally vaporizes. This enables dirt and dirty capillary water to be washed out when the expanding vapor presses out of the pores, capillaries and fissures of the exterior coat. Furthermore, this makes the impregnation of the deeply cleansed exterior coat possible, as required.

In the case of severely dirty surfaces, the most severe dirt is removed by holding the nozzle tangential to the area. Thus, the dirt particles are loosened by the power of the jet. After doing this, the surface area is cleansed as above set forth.

For the purpose of impregnation, various solutions may be used e.g., solutions which are composed of certain mixtures containing alkyl, alkoxy, and silan. These solutions are dissolved in alcohol and then applied to the cleansed area, either by use of a brush or by spraying. Alternatively, the building materials are impregnated with this solution after first being cleansed. These solutions are usually based on compositions which, under the influence of damp air become hydrolyzed, and, thus, form a direct binding to the binding mediums of the building materials. The groups of organic silicate acid compositions are directed to the surface area, and the water resistant effect is attained by covering the area of the material evenly with a coating of a composition of a hydrophobic organic group which increases the interior tension toward the water. This coating on the surface area increases the exterior tension towards water and thus reduces the suction capacity of the exterior area capillaries.

The method depends on the use of special aggregates, the pressure of the water is produced by a pump and in which the water is heated to a minimum of 100°C. An operating pressure of 20 atm. is best adapted at the entrance of the nozzle. When the heated water or steam passes the nozzle, the pressure drops rather quickly to atmospheric pressure, whereas the water temperature does not drop at the same rate. As a result, the water is thus overheated at the entrance of the nozzle due to this delay in boiling. Vaporization begins probably in the nozzle outlet. The velocity of the jet is increased considerably. Vaporization is only com-

pleted when the water has absolutely entered the pores and capillaries. This facilitates the required depth effect. Since all the water which is available in the pores and capillaries of the exterior area or introduced to these, conducted by the vaporizing of the overheated water, the pores become completely empty of water. Only a little dampness remains on the surfaces of the pores and capillaries. This dampness, as has already been stated, is the bases upon which the impregnation solution mediums bind with the binding mediums of the material. The cleansing technique according to the invention is thus conducive to the material being depth impregnated with solutions appropriate to this purpose.

The distance between the nozzle and the surface area to be cleansed depends upon the operating pressure and the water temperature. To attain the required effect, the water jet should be concentrated when it hits the surface area. It must possess sufficient energy so that the vaporization may enter into the exterior coating. Should the distance be large, the jet loses itself with respect to concentration because too much water vaporizes during the boiling procedure while, at the same time, the jet temperature falls.

Also the form of the nozzle is of significance towards attaining the required technical effect. A certain minimum quantity of water per time unit must be released at the pressure and temperature required for operation to prevent all the water from vaporizing when the jet leaves the nozzle.

Furthermore, there is an aspect noticeable in this invention technique which can contribute towards the attainment of the required effect. When the well concentrated jet touches the surface area, a part of the jet

pressure is retained in the pores as a result of the jet impulse, which leads to a reduction in vaporization and the steam bubble composition in the jet is reduced also. When the nozzle is turned to the side the pressure is temporarily reduced. This leads to a speedy vaporization of the over-heated water and contributes very much to the attainment of the desired technical effect. Based on measurements, it has been found that with the hot water at a discharge temperature of 130°C. at the discharge end of the directing nozzle, the nozzle has to be held at a maximum distance of two centimeters from the surface being cleaned in order to achieve proper vaporization of the water in the hollow capillary compartments.

We claim:

1. Method of cleansing the exterior surface of a building of masonry, stone, brick or the like, comprising
  - a. directing a jet of water at a temperature not less than about 100°C. from a nozzle at a pressure of about 20 atm against the surface to be cleaned,
  - b. disposing said water jet at approximately right angles to such surface with the end of the nozzle spaced at a maximum distance of about 2 cm from the surface, and
  - c. moving the water jet parallel to such surface while maintaining same in said right angle position, whereby due to the proximity of the jet to such surface the greater volume of water does not vaporize before touching the surface and part of the water is forced into the pores for achieving vaporization therein.
